(No Model.)

G. H. FULLER.

FOLDING SEAT.

No. 245,153.

Patented Aug. 2, 1881.

UNITED STATES PATENT OFFICE.

GEORGE H. FULLER, OF SAN FRANCISCO, CALIFORNIA.

FOLDING SEAT.

SPECIFICATION forming part of Letters Patent No. 245,153, dated August 2, 1881.

Application filed July 30, 1880. (No model.)

To all whom it may concern:

Be it known that I, GEORGE H. FULLER, of the city and county of San Francisco, and State of California, have invented an Improved 5 Folding Seat; and I hereby declare the following to be a full, clear, and exact description thereof.

My invention consists in a specific improvement, hereinafter claimed, by which the chair-frame is greatly strengthened.

Referring to the accompanying drawings for a more complete explanation of my invention, Figure 1 is a perspective view of the seat unfolded for use. Fig. 2 is a sectional view with 10 the parts folded. Fig. 3 is a side view of the seat partly folded.

A A are the back legs of the seat, and they are continued up to form the sides a of the back. The bars B unite these side pieces and 20 form the back-support, and the rails C unite the rear legs to strengthen them, the whole forming the back and back-leg frame.

The front-leg frame consists of the legs D, which are continued up above the seat, and 25 so curved that their upper ends rest against the front of the backs a. They are connected by rails E below the seat in the usual manner, so as to strengthen them. At the upper end these front-leg extensions are beveled off, as 30 shown at d, so as to rest flush against the front of the side pieces, a.

Links F are bolted upon each side of the side pieces, a and D, at c c', and when the seat is unfolded these links stand in line with the 35 upper part, d, and act as direct thrust-bearings to lock the front legs in place and prevent their moving when the seat is unfolded and in use.

The side rails, G, of the seat extend from 40 the rear to the front legs at the proper height, as shown, and are pivoted to them at b b', so that when unfolded they are in a position about parallel with the floor, while the links F stand at an acute angle with them.

45 The points on the back legs where the seat and links are pivoted are the fulcrums about which the front-leg frame moves, in the manner of a parallel ruler, and without any supplemental braces or supports of any sort. The 50 side rails of the seat are connected by the longitudinal rails H, and a rigid bottom is secured to the seat-frame, as shown. The whole seat, when opened, is thus made very rigid, and it is particularly adapted to be used for 55 long seats or settees, and in halls, where it is

often necessary to pack the seats into a smaller compass to clear the floor. The curve of the back and back legs, the front legs, and the seat-bottom correspond so nearly that when the parts are folded together the front legs 60 follow the curve of and rest upon the back legs, while the seat follows the curve of the back and lies between the front and rear legs, so that the whole device only occupies a space equal to the thickness of the legs. 65

The distance between the pivots b b' is somewhat greater than the distance between the pivots c c', and the distance between the pivots b c upon the rear legs is also greater than the distance between the pivots b' c' upon the front legs. By this construction the front legs move about the rear ones like the sides of a parallel ruler, guided by the seat and the links F; but the above-mentioned differences in length, while allowing them to fold closely 75 upon the rear legs, will throw the bottom of the front legs out and draw the upper ends, d, in until they rest against the rear portion, a, and are locked or braced by the links F, without the aid of other connections or braces. 80

I am aware that the patent of Gardener, October 10, 1871, shows a folding chair having front, back, and seat all pivoted together, the connection between the front and back frames being made by a link embedded in wood and 85 set out of line with the front standards. I am also aware that the patents of Collignon and Vaill, of November 24, 1868, and February 27, 1877, show folding seats wherein the front frames are joined to the back by an intermediate connecting-piece, which forms the round 90 of the chair, and I do not claim such connections; but

What I do claim is—

The described folding seat, consisting of 95 the curved back-frame, a the front-leg frame, composed of standards which form the arms and front legs of the seat, and which are provided with beveled ends, the link F, pivoted to the back-frame and to the front-leg frame, 100 so as to be in line with such front-leg frame when the seat is open, and the seat G, pivoted at b b' to the front and back frame, all substantially as described.

In witness whereof I have hereunto set my 105 hand.

GEORGE H. FULLER.
